RAILWAY SWITCH OPERATING APPARATUS

Herbert L. Bone, Forest Hills, Pa., assignor to The Union Switch & Signal Company, Swissvale, Pa., a corporation of Pennsylvania

Application November 12, 1943, Serial No. 510,005

8 Claims. (Cl. 246—242)

My invention relates to railway switch operating apparatus, and particularly to railway switch operating apparatus of the so-called "dual-control" type in which means are provided for operating a switch either by power or by hand depending upon the position of a manually operable selector lever.

The principal object of my invention is to insure the safety of trains and vehicles moving over railway switches.

Another object of my invention is the provision in apparatus of the type described of means for preventing creeping of the switch throwing mechanism from either extreme position due to vibration.

Another object of my invention is the provision of novel means operated by the selector lever for cutting off the supply of power to the power operating means before the hand operating means can be connected with the switch.

A further object of my invention is the provision of a novel and improved circuit controller for detecting any failure of the switch points to occupy their proper positions relative to the stock rails in either extreme position of the switch.

A still further object of my invention is the provision of novel and improved latching mechanism which may be incorporated into the circuit controller when desired, and which, when utilized, provides means whereby, if the indication contacts of the circuit controller are improperly forced open, as by a train trailing the switch, when the switch points are locked in either extreme position, these contacts will be positively held open by the latching mechanism until the latching mechanism is manually operated to release the contacts.

According to my invention, the mechanism includes a main switch operating crank selectively connected through the medium of a clutch operated by a manually operable selector lever with a first gear operated by a hand throw lever or a second gear operated by an electric motor. The hand throw lever and selector lever are on a common axis and are interlocked in a manner which prevents operation of the hand throw lever except when the selector lever occupies its "hand throw" position. The selector lever operates the clutch through the medium of a bell crank provided on the inner end of the lever and cooperating with a pivoted yoke which straddles the clutch. The clutch is operatively connected through suitable linkage with motor cut-out contacts in such manner that operation of the clutch to the motor operating position will open these

contacts. Creeping of the mechanism from either extreme position due to vibration is prevented by a spring pressed plunger arranged to cooperate with locking cam surfaces formed in the periphery of one of the power gears. The main switch operating crank cooperates with a suitable throw bar to reverse the switch and also with a locking plunger which latter cooperates with a lock rod secured to the switch points to lock the switch in its two extreme positions. The locking plunger carries a rack which actuates a circuit controller for controlling the energization of the motor. This controller includes indication contacts. These contacts are arranged in pairs and are moved to their operated positions either by a cam operated by said rack or by a point detector mechanism operated by a point detector rod connected to the switch points. The point detector includes latch mechanism which is effective to 15 move the indication contacts in their operated positions if they are moved to these positions by displacement of the switch points from their normal locked positions, due for example, to a train trailing the switch.

20 Other objects and characteristic features of my invention will become apparent as the description proceeds.

I shall describe one form of railway switch operating apparatus embodying my invention, and shall then point out the novel features thereof in claims.

In the accompanying drawings, Fig. 1 is a top plan view showing one form of railway switch operating apparatus embodying my invention, the 25 covers for the apparatus being removed or broken away to illustrate the detail parts. Fig. 2 is a longitudinal vertical sectional view of the apparatus illustrated in Fig. 1. Fig. 3 is a view, partly diagrammatic and partly in horizontal 30 section, showing certain of the parts of the apparatus illustrated in Figs. 1 and 2 connected with a railway switch in the intended manner. Fig. 4 is a bottom view of the clutch sleeve 25 forming part of the clutch of the apparatus 35 shown in Figs. 1 and 2. Fig. 5 is a top plan view of the gear wheel 15 forming part of the apparatus illustrated in Figs. 1 and 2. Fig. 6 is a top view of the clutch sleeve 24 forming part of the 40 apparatus illustrated in Figs. 1 and 2. Fig. 7 is a bottom view of the gear wheel 17 forming part of the apparatus illustrated in Figs. 1 and 2. Fig. 8 is a view similar to Fig. 7 45 showing a modified form of gear wheel sometimes employed in the apparatus in place of the gear wheel 17. Fig. 9 is a sectional view taken on the 50 55

line IX—IX of Fig. 1. Fig. 10 is a top plan view showing, on an enlarged scale, a portion of the circuit controller G forming part of the switch operating apparatus illustrated in Figs. 1 and 2. Figs. 11 and 12 are sectional views taken on the lines XI—XI and XII—XII, respectively, of Fig. 10. Figs. 13 and 14 are sectional views taken on the lines XIII—XIII and XIV—XIV, respectively, of Fig. 2. Fig. 15 is an exploded view in isometric projection of a portion of the circuit controller G 10 shown in Fig. 10.

Similar reference characters refer to similar parts in each of the several views.

Referring to the drawings, the reference character 1 designates a housing provided with removable covers 2 and 3, and adapted to be mounted adjacent a railway track switch S shown diagrammatically in Fig. 3. Journaled in vertically aligned bearings 4 and 5 disposed within the housing 1 is a vertically extending shaft 6, the lower end of which carries a crank 7. This crank extends in opposite directions from the shaft, and is provided on its lower side with a crank pin 8 carrying a roller 9, and on its upper side with rounded upstanding projections 10 and 11 (see Fig. 3) disposed on opposite sides of the shaft. The roller 9 cooperates with a cam slot 9a formed in an operating rod O, while the projections 10 and 11 cooperate, respectively, with spaced recesses 10a and 11a formed in the underside of a slide bar N. The operating rod O is slidably mounted in the bottom of the casing 1 at one side of the axis of the shaft 6, and is operatively connected at one of its outer ends with the switch S. The slide bar N is slidably mounted in the bottom of the casing 1 in a position in which it intersects the operating rod O at right angles, and is provided at its left-hand end with a locking plunger 12 provided with vertically offset and longitudinally spaced locking dogs 12a and 12b (Fig. 2) which are adapted to selectively enter spaced notches 13a and 13b provided in a lock rod L operatively connected with the switch points of the switch S. The lock rod L is of well-known construction, and is slidably mounted in the bottom of the casing 1 at right angles to the slide bar N, as is obvious.

The portion of the switch operating apparatus thus far described is essentially the same as that described and claimed in Letters Patent of the United States No. 1,293,290, granted to William Zabel on February 4, 1919, for Railway traffic controlling apparatus, and its operation, briefly described, is as follows: When the operating rod O and the slide bar N are in their normal positions, and the switch points of the switch S are in their corresponding positions, as shown in Fig. 3, the locking dog 12a is disposed within the notches 13a in the lock rod L, and under these conditions the switch points are securely locked in their normal positions by the locking dog 12a.

When it is desired to reverse the switch S, the shaft 6 is rotated in a clockwise direction from the extreme position shown to its opposite extreme position. The initial part of this rotation, usually about the first 30°, causes the projection 10 on the crank 7 to engage the left-hand wall of the recess 10a in the slide bar N, and move the slide bar toward the left far enough to withdraw the locking dog 12a from the notches 13a in the lock rod L. During this initial movement of the crank the roller 9 whose initial position was at the left-hand end of the cam slot 9a is moved to the medial portion of the slot, that is to say, to a point just a little to the left of the junction

5 of the curved and straight walls thereof, but due to the curvature of the upper wall of the cam slot, this movement of the roller does not cause any movement of the operating rod O. It will be seen, therefore, that during the first part of the movement of the crank 7 the slide bar N is moved to unlock the switch points, but the operating rod O and the switch points remain stationary. However, in the continued movement of the crank, the roller 9 engages the lower straight side of the cam slot 9a and moves the operating rod O in the direction that the crank is moving to thereby move the switch points to their reverse positions. This latter or intermediate movement of the crank will usually rotate the crank through an angle of approximately 180°. Upon further continued movement of the crank, projection 11 enters the recess 11a and imparts a second movement to the slide bar N in the same direction as the first movement, which latter movement causes the locking dog 12b to enter the notches 13b in the lock rod L and lock the switch in its reverse position.

When the parts have been operated to the positions just described, and the crank is rotated in a counterclockwise direction to restore the parts to the positions shown, the sequence of movements of the operating rod and slide bar are maintained, but the directions of the movements are reversed.

For convenience I shall hereinafter refer to the initial movement of the crank from either extreme position toward the other as the unlocking stroke, the intermediate portion as the switch operating stroke, and the final movement as the locking stroke.

It should be particularly pointed out that with the apparatus constructed in the manner just described, upon the completion of the switch operating stroke in either direction of rotation of the crank 7, the roller 9 will have just entered the curved portion of the cam slot 9a, and that when the parts are in these positions if the crank is prevented from rotating in the direction to move the roller out of the curved portion of the cam slot, the switch will be effectively held, by the cooperation between the roller and the operating rod, in the extreme position it then occupies irrespective of the fact that it is unlocked. It follows, therefore, that if suitable precautions are taken to prevent the crank from creeping upon the completion of the switch operating stroke, trains can be safely moved over the switch even though it is not locked by the locking plunger. For the purpose of preventing the crank from creeping under these conditions, and also when the switch is locked in either extreme position I provide anti-creep means which I shall now describe.

As here illustrated, these means comprise a spring pressed plunger 14 (see Fig. 1) which operates with a main bevel gear 15 rotatably mounted on the shaft 6 directly above the lower bearing 4. The bevel gear 15 is operatively connected with power driving means here shown as an electric motor M, through suitable reduction gearing indicated in the drawings by dash lines 16, and is arranged to be at times connected with the shaft 6 by suitable clutch mechanism which I shall described presently. The spring pressed plunger 14 is mounted in an auxiliary housing 14a bolted to the side of the main casing 1, and cooperates at its inner end with four inclined cam surfaces 15a, 15b, 15c and 15d formed on the periphery of the main bevel gear. The cam

surface 15a is so positioned that any movement of the mechanism away from its full normal position will cause the plunger 14 to ride up onto this cam surface; the cam surface 15d is so positioned that any movement of the mechanism away from its full reverse position will cause the plunger 14 to ride up onto this cam surface; the cam surface 15b is so positioned that any movement of the mechanism away from the end of the switch operating stroke in the direction to move the switch from its normal toward its reverse position will cause the plunger 14 to ride up onto this cam surface, and the cam surface 15c is so positioned that any movement of the mechanism away from the end of the switch operating stroke in the direction to move the switch from its reverse to its normal position will cause the plunger 14 to ride up onto this surface. The strength of the spring 14b which urges the plunger into frictional contact with the periphery of the main bevel gear is such that the force necessary to cause the plunger to ride up onto any one of the cam surfaces 15a, 15b, 15c or 15d is greater than any force resulting from vibration tending to cause the switch operating mechanism to creep, but is insufficient to interfere with the normal operation of the mechanism by the power driving means or by the hand throw means presently to be described.

An auxiliary bevel gear 17 (Figs. 2 and 9) is also rotatably mounted on the shaft 6 between the upper bearing 5 and the upper end of a bushing 18, the lower end of which bushing rests on a shoulder 19 formed on the shaft 6. The bevel gear 17 meshes with a second bevel gear 20 fixed to the end of a horizontally extending sleeve 21 rotatably mounted in suitable bearings provided in a bearing support 22 bolted to the side of the main casing 1. Secured to the outer end of the sleeve 21 is a hand throw lever 23, by means of which the sleeve 21, and hence the bevel gear 20 may at times be rotated between two extreme positions.

The main bevel gear 15 and the auxiliary bevel gear 17 are arranged to be selectively connected with the shaft 6 to permit the shaft to be operated by the motor or by the hand throw lever 23, by means of a clutch mechanism A (see Fig. 9). As here shown, this clutch mechanism comprises two sleeves 24 and 25 which are mounted on the shaft 6 for vertical sliding movement between the two gears 15 and 17, but which are constrained to rotate with the shaft 6 by means of integral internal splines 26 which cooperate with corresponding splines 6a formed on the shaft. The two sleeves 24 and 25 are secured together at their confronting ends to cause them to act as a unit, and are provided at their upper and lower ends, respectively, with circumferential flanges 24a and 25a which form confronting shoulders 24b and 25b. Surrounding the sleeves 24 and 25 between the shoulders 24b and 25b is a compressed coil spring 28. One end of this spring engages a cupped spring thrust washer 270 and constantly urges it to the position in which it engages the shoulder 24b, and the other end of this spring engages a cupped spring thrust washer 27 and constantly urges it to the position in which it engages the shoulder 25b.

The lower end of the sleeve 25 is formed with tapered projections 29 (see Figs. 4 and 9) which cooperate with tapered recesses 30 (see Figs. 2 and 5) provided in the hub of the bevel gear 15, whereby when the clutch mechanism is in its lower position as shown, the shaft 6 is connected

to the main bevel gear 15 to enable the mechanism to be power operated in the normal manner. The projections 29 are unevenly spaced about the sleeve, three such projections being provided. It will be seen, therefore, that with the parts constructed as shown, the clutch can become connected with the gear wheel 15 in only one angular position. It should be understood, however, that any desired number of projections may be provided.

The upper end of the sleeve 24 is provided with a single projection 31 (see Fig. 6) which cooperates with a recess 32 (see Fig. 7) formed in the lower face of the bevel gear 17. When it is desired to permit the switch to be locked in either extreme position by means of the hand throw lever, the projection 31 will usually be made with an angular length which is just slightly less than the angular length of the recess 32, and the parts are so proportioned that under these conditions rotation of the hand throw lever 23 between its two extreme positions will rotate the switch actuating shaft between its two extreme positions in the same manner that this shaft is rotated between its two extreme positions by power operation when the clutch is in engagement with the bevel gear 15. For example the projection 31 may have an angular length of just slightly less than 180°, while the recess 32 may have an angular length of just slightly more than 180°. It will be understood, however, that this proportioning of the parts is given merely by way of example, and not by way of limitation, and that other satisfactory proportionings of the parts may be readily effected.

Under some conditions of operation it is desirable to be able to reverse the switch by the hand throw lever 23 without causing it to become locked by the lock rod in its extreme positions.

With the mechanism constructed as shown, this result can be accomplished by replacing the bevel gear 17 with a bevel gear 17a (see Fig. 8) having a recess 32a of longer arc than the recess 32 of the gear 17. For example, the recess 32 may be made 240° long. When the gear 17 is replaced by the gear 17a, the anti-creep mechanism described hereinbefore will act to retain the switch points in either extreme position to which they are moved by the hand throw lever even though the switch is not locked by the lock rod in such extreme position, thus permitting trains to be safely moved over the switch at reduced speeds.

The overall length of the clutch mechanism including the projections 29 and 31 is such that it cannot be disengaged from one gear until it first becomes engaged with the other gear. It follows, therefore, that the shaft 6 will always be engaged with either the power or the hand throw gearing.

The clutch mechanism A is arranged to be moved longitudinally on the shaft 6 to effect the desired driving connection between the bevel gear 17 and the shaft 6 or the bevel gear 15 and the shaft 6 by means of a U-shaped shifter fork 35 (Figs. 1, 2 and 9) the arms 35a and 35b of which straddle the clutch mechanism and are pivotally supported on pivot pins 36 mounted in spaced lugs 37 provided on a removable plate 38 bolted to one side of the housing 1. Secured to the arms 35a and 35b on opposite sides of the clutch mechanism are spaced rollers 39, the upper ones of which overlie the flange of the spring cup washer 270 and the lower ones of which underlie the flange of the spring cup washer 27. The spacing between the two rollers on each arm is made

slightly greater than the spacing between the upper and lower sides respectively of the flanges on the two cup washers when these washers are engaging the associated shoulders 24b and 25b, for a purpose which will appear presently.

The web portion 35c of the shifter fork 35 is provided with an opening 40 which cooperates with a rounded pin 41 formed on the inner end of a shaft 42 in eccentric relation with respect to the axis of the shaft. The shaft 42 extends through, and is rotatably mounted in, the sleeve 21, and is provided at its outer end with a selector lever 43 by means of which the shaft may at times be oscillated.

The operation, as a whole, of the portion of the apparatus thus far described is as follows: Normally the selector and hand throw levers both occupy the positions in which they are shown in Fig. 1, which is the position for power operation, and under these conditions, the shifter fork 35 is rotated by means of the rounded pin 41 to its lowermost position. The parts are so proportioned that, when the shifter fork occupies this position, if the projections 29 on the lower end of the clutch sleeve 25 are then in alignment with the recesses 30 in the bevel gear 15, the clutch will move to its lowermost position, and will thereby condition the apparatus for power operation in the manner pointed out hereinbefore. When the clutch assembly is in its lowermost position, it is supported by the top face of the hub of the gear 15, and the parts are further so proportioned that all four rollers 39 will be clear of the flanges of the spring cup washers, so that under power operation no load is carried by these rollers. It will be understood, of course, that when the mechanism is operated by the motor, the switch actuating shaft 6 will be rotated through its full operating stroke, so that the switch will become locked in either extreme position to which it is moved.

If, when the selector lever is moved to the power operating position, as shown, the projections 29 on the clutch sleeve 25 do not align with the recesses 30 in the hub of the bevel gear 15, so that the clutch sleeve is prevented from moving to its lowermost extreme position by engagement of the lower ends of the projections 29 with the upper side of the hub of the bevel gear, the shifter fork 35 will still be rotated to its lowermost position, but under these latter conditions, the rollers 39 will act through the cup washer 270 to exert a force on the spring 28 which causes it to become compressed and bias the clutch assembly toward its lowermost position. As a result, as soon as the bevel gear 15 is rotated by the motor to the position in which the projections 29 align with the recesses 30, the clutch will immediately snap to its lowermost position in which it is shown in the drawings.

When the switch is in condition for motor operation, the bevel gear 17 is disconnected from the switch actuating shaft 6, and the hand throw lever is therefore disconnected from the switch.

When it is desired to disconnect the motor from, and connect the hand throw lever 23 with the shaft 6, the selector lever is rotated from the motor operating position in which it is shown in the drawings to its opposite extreme or hand throw position. This rotation acts through the shaft 42 and rounded pin 41 to rotate the shifter fork from its lowermost to its uppermost position. During this rotation the lower rollers 39 on the shifter fork engage the underside of the flange on the lower spring cup washer 27 and move it up-

wardly with the shifter fork. The upward movement of the cup washer, in turn, exerts a force on the spring 28 which is transmitted through the spring and cup washer 270 to the interconnected clutch sleeves, and under normal conditions this force will cause the sleeves to move upwardly as soon as the shifter fork starts to move. However, should the switch operating apparatus happen to be standing with the power gear train stopped by the inertia of the rotating parts upon the completion of the previous reversal of the mechanism, the static torque which then exists between the engaging sides of the projections 29 and recesses 30, may be sufficient to prevent the assembly from starting to move upwardly even though spring 28 becomes fully compressed. The parts are so proportioned that under these latter conditions, the flange of the cup washer 27 will move into engagement with the flange of the cup washer 270 before the shifter fork reaches its upper extreme position, and when this happens, a positive force will be exerted on the clutch sleeves, which force is sufficient to overcome the static torque between the lower sleeve and the gear wheel 15 and thus cause the clutch assembly as a whole to move upwardly under the bias of the compressed spring 28.

When the clutch assembly starts to move upwardly, if the recess 32 in the bevel gear 17 is then in alignment with the projection 31 on the sleeve 24, as will be the case when the switch and hand lever occupy corresponding extreme positions and the switch is fully locked in the extreme position it then occupies, the spring 28 will cause the clutch to move to its upper extreme position in which the projection 31 enters the recess 32. The bevel gear 17 will then be connected with the shaft 6 in such manner that the switch may be rotated between its two extreme positions and locked in either extreme position to which it is moved by the hand throw lever 23 in the same manner that it is rotated between its two extreme positions and is locked in either extreme position by power operation. If, however, the recess 32 in the bevel gear is not in alignment with the projection 31 or the sleeve 24 of the clutch assembly when the clutch assembly starts to move upwardly, the spring 28 will become compressed and permit the shifter fork to complete its upward movement. Under these conditions, as soon as the hand throw lever is rotated to the position in which the recess 32 aligns with the projection 31, the spring 28 will act to force the clutch assembly to its full upper position. This alignment of the recess with the projection 31 will always occur at some point in the stroke of the hand throw lever, and if the switch happens to be in a position opposite to that of the hand throw lever when the selector lever is operated to the hand throw position, then the hand throw lever will rotate freely without engaging the clutch until the hand throw lever is fully reversed.

Associated with the hand throw lever 23 and the selector lever 43 is a mechanism D including means for locking the levers against movement by unauthorized persons and means for interlocking the levers in such manner that the hand throw lever cannot be operated unless the selector lever occupies the hand throw position. This mechanism forms no part of my present invention, and may for example, be similar to that described and claimed in Letters Patent of the United States No. 1,887,376, granted to G. V. Jefferson and E. J. Little on November 8, 1932, for Railway switch operating apparatus. Inasmuch as the mechanism

D forms no part of my present invention it is deemed unnecessary to describe it in detail herein.

Mounted in the left-hand end of the housing 1 above the lock rod L and the slide bar N is a circuit controller G for indicating when the switch is locked and the closed switch point is in proper engagement with the associated stock rail. As best seen in Figs. 10 to 13, this circuit controller comprises a suitable supporting framework 50 provided with aligned bearings 51 and 52 in which a horizontal camshaft 53 is journaled. The camshaft 53, which is of rectangular cross section except for a rounded portion at each end which fits into the associated bearing, is adapted to be rotated or oscillated in response to longitudinal movements of the slide bar N, and for this purpose the shaft 53 has fixed thereto a gear wheel 54 which meshes with the teeth of a rack bar 45 secured to the upper face of the locking plunger 12. Mounted on the camshaft 53 on opposite sides of the gear wheel 54 are a plurality of driving collars of insulating material, each designated by the reference character 55 with a suitable distinguishing exponent. Each driving collar 55 is provided with a square hole which has a sliding fit on the camshaft 53, and as clearly shown in Fig. 11, each driving collar comprises a comparatively narrow web and a peripheral flange extending in each direction from the outer edge of the driving collar. A portion of the peripheral flange of each driving collar is tapered, and the tapered portion is provided with serrations or teeth (not shown) around its entire circumference. Each driving collar 55 carries a metal contact segment of electro-conductive material designated by the reference character 56 with the same distinguishing exponent as the exponent for the reference character of the associated collar. Each contact segment is in the form of the segment of a ring, the base of which is tapered to fit the tapered portion of the periphery of the associated driving collar. The base of each driving collar is also provided with serrations or teeth (not shown) which match the teeth on the periphery of the insulated driving collars. Each contact segment 56 cooperates at its periphery with a contact finger designated by the reference character 57 with the same distinguishing exponent as the reference character for the associated contact segment. For example, the contact segment 56a cooperates with the contact finger 57a to at times close a contact 56a-57a. The periphery of each contact segment may have any desired length, and due to the mating teeth on the driving collars, the segment may be turned to any desired position relative to the camshaft 53. The two contact segments 56a and 56b are connected together by a bar 58 and are so adjusted that these segments will each engage the associated contact finger to close the contacts formed thereby at all times except when the slide bar N is in the extreme position in which it locks the switch points in their normal positions. The two contact segments 56c and 56d are similarly connected together by a bar 59 and are so adjusted that these segments will each engage the associated contact fingers at all times except when the slide bar N occupies the extreme position in which it locks the switch points in their full reverse positions. The contacts 56a-57a, 56b-57b, 56c-57c and 56d-57d may be used in a well-known manner to control the circuits for the motor M or for any other desired purpose.

The circuit controller also comprises a pair of contact fingers 60a which are connected together for simultaneous movement by an insulating bridge 61a, and a pair of contact fingers 60b which are connected together for simultaneous movement by an insulating bridge 61b. The fingers 60a and 60b are biased by their own resilience to lower positions in which they engage associated lower stationary contact members 62a and 62b to close a pair of contacts 60a-62a and a pair of contacts 60b-62b, but are adapted to be at times moved upwardly, by means of point detector mechanism which I shall now describe, to upper positions in which they engage an upper stationary contact member 63 to thereby close a contact 60a-63 and 60b-63.

As best seen in Figs. 11 and 15, the gear wheel 54 which drives the camshaft 53 is formed with oppositely disposed hubs 54a and 54b, and mounted on the camshaft 53 between the hub 54a and the driving collar 55b is a washer 65a and a bushing 66a. A washer 65b and a bushing 66b are similarly mounted on the camshaft between the hub 54b and the cam 55c. The bushings 66a and 66b are formed with portions 67a and 67b which are eccentric with respect to the camshaft, and with other portions 68a and 68b which are concentric with respect to the camshaft, and are disposed on the camshaft with the concentric portions 68a and 68b nearest to the adjacent hubs 54a and 54b, respectively. The hubs 54a and 54b carry cams 69a and 69b, respectively, which are connected to the gear 54 to rotate therewith in a manner which I shall describe presently. The cam 69a is provided in its periphery with an arcuate notch 70a (see Fig. 12), and is adapted when rotated to actuate the contact fingers 60a through the medium of a roller 71a attached to the insulating bridge 61a. The cam 69b is likewise provided in its periphery with an arcuate notch 70b (see Fig. 2), and is adapted when rotated to actuate the contact fingers 60b through the medium of a roller 71b attached to the insulating bridge 61b. The parts are so proportioned that when either notch is opposite the associated roller, the fingers are free to move to their lowermost position, but that, when the notches are not opposite the rollers, the associated fingers will be lifted into engagement with contact member 63. The cams 69a and 69b are so arranged and the notches 70a and 70b are of such lengths that both sets of fingers 60a and 60b will be lifted when the slide bar N is in transit, but that one pair of fingers will normally be permitted to assume their lower positions when the slide bar N is at one extreme end of its stroke, and the other pair of fingers will normally be permitted to assume their lower positions when the slide bar N is at the other extreme end of its stroke, as will be described more fully hereinafter.

The means referred to hereinbefore for operatively connecting the cams 69a and 69b with the gear 54 comprises a driving pin 75a (see Figs. 10 and 15) which projects from the side of the gear 54 contiguous to the cam 69a for cooperation with one or the other of two radial slots 76a and 77a formed in the hub of the cam 69a, and a driving pin 75b which projects from the opposite side of the gear 54 for cooperation with one or the other of two radial slots 76b and 77b formed in the hub of the cam 69b. The spacing between the slots 76a and 77a is such, and the parts are so arranged, that when the pin 75a is within the slot 76a the notch 70a in the cam 69a

will align with the roller 70a when and only when the slide bar N occupies the extreme position in which it is shown in the drawings, but that when the pin 75a is within the slot 71a the notch 70a in the cam 69a will then align with the roller 70a when and only when the slide bar N occupies its opposite extreme position. Similarly, the spacing between the slots 76b and 77b is such that when the pin 75b is within the opening 76b, the notch 70b in the cam 69b will align with the roller 71b when and only when the slide bar N occupies its normal extreme position shown in the drawings, whereas when the pin 75b is within the slot 77b, the notch 70b in the cam 69b will align with the roller 71b when and only when the slide bar N occupies its reverse extreme position. The cams will usually be mounted on the hubs in such positions that the notch in one cam will align with the associated roller in one extreme position of the switch and the notch in the other cam will align with the associated roller in the other extreme position of the switch.

In order to enable the switch operating apparatus to be used in either a right-hand or a left-hand installation, it is desirable to be able to readily change the cams 69a and 69b from the positions in which the associated pin 75 extends into either one of the slots 76a and 77a to the position in which it extends into the other opening, and for this purpose the cams 69a and 69b are provided at the side opposite to that in which the slots 76 and 77 are formed with counterbores 78a and 78b. These counterbores are slightly larger in diameter than the adjacent washers 65a and 65b, and the parts are so proportioned that when it is desired to rotate a cam from the position in which the associated pin 75 enters the one slot in the cam to that in which it enters the other slot this can be done by merely sliding the cam outwardly along the associated hub of the gear wheel 54 far enough to disengage the pin from the slot, rotate the cam until the other slot aligns with the pin, and then move the cam inwardly along the hub to the position in which the pin enters the desired slot. The cams are held in the position in which the associated pin 75 is within the desired slot by means of coil springs 79a and 79b disposed in the counterbores. As here illustrated the cam 69a occupies the relative position on the hub 54a in which the associated pin 75a is within the slot 76a, while the cam 69b occupies the relative position on the hub 54b in which the associated pin 75b is within the slot 77b. With this arrangement, insofar as the control of the contact fingers 60a and 60b by the cams 69a and 69b is concerned, the contact fingers 60a will be held in the positions in which the contacts 60a-62a are open and the contact 60a-63 is closed except when the slide bar N occupies the extreme position shown in Fig. 3, and the contact fingers 60b will be held in the positions in which the contacts 60b-62b are open and the contact 60b-63 is closed at all times except when the slide bar N occupies the extreme position opposite to that in which it is shown in Fig. 3.

The contact fingers 60a and 60b are further controlled in accordance with the positions of the switch points through the medium of two cams 81a and 81b (Figs. 10 and 15) which are formed on the arms 82a and 82b of a U-shaped contact operating member 82, and which cams cooperate respectively with the rollers 71a and 71b at one side of the arcuate cams 69a and 69b. The arms 82a and 82b are journaled interme-

diate their ends on the portions 68a and 68b of the bushings 66a and 66b which are concentric with respect to the camshaft 53, and are provided at their free ends with open end slots 84a and 84b which slidably receive pins 85a and 85b mounted on the short laterally projecting arms 86a and 86b of two operating levers 87a and 87b. The levers 87a and 87b are journaled on the portions 67a and 67b of the bushings 66a and 66b eccentric with respect to the camshaft 53 and are further provided with forked depending arms 88a and 88b which are pivotally connected to adjustable operating rods 89a and 89b, respectively. The free ends of the operating rods 89a and 89b, in turn, are connected with the upstanding arms 90a and 90b (see Fig. 13) of point detector levers 91a and 91b pivotally supported on pivot pins 192a and 192b mounted in suitable supports formed in the housing 1.

The levers 91a and 91b are provided in addition to the upstanding arms 90a and 90b with depending feet 92a and 92b which carry rollers 93a and 93b and with laterally projecting arms 94a and 94b. Tension springs 95a and 95b are connected at one end to the arms 94a and 94b and at the other end to lugs 96a and 96b cast on the housing 1, and constantly bias the levers to positions in which the associated roller 93 engages a point detector rod D slidably mounted in the housing 1 for movement in directions parallel to the camshaft 53. The detector rod D is adapted to be adjustably connected to the movable switch points of the switch S as indicated diagrammatically in Fig. 3, by a well-known form of adjustable connection (not shown), and is provided with an annular notch or recess 97 which aligns with the roller 93a when and only when the switch points occupy their proper normal positions and with the roller 93b when and only when the switch points occupy their proper reverse positions.

The bushings 66a and 66b are provided with square holes to fit the camshaft 53, and it follows that these bushings can be mounted on the camshaft in any one of four positions spaced 90° apart. The eccentricity of the eccentric portions 67a and 67b is arranged so that the line extending from the eccentric center to the center of the shaft is spaced 30° from the nearest line extending from the center of the shaft at right angles to one of the sides of the square hole, and the bushings are assembled on the shaft in such relative positions and the parts are so proportioned that when the notch 97 in the point detector rod D is in alignment with either roller 93 the spring 95 connected with the point detector lever 91 to which such roller is attached will rotate this lever to the position in which the roller enters the notch, and that under these conditions both springs 95 will act through the associated point detector lever 91, the associated operating rod 89, operating lever 87, pin 85, and open end slot to rotate the contact operating member 82 to the position in which a stop shoulder 82c (see Fig. 12) formed in the yoke portion of the contact operating member engages a stop arm 101 secured to the frame 50 of the controller. The parts are further so proportioned that when the operating member 82 occupies this position, the cams 81a and 81b will be out of the path of movement of the rollers 71a and 71b, so that insofar as the control of contact fingers 60a and 60b by the point detector rod D is concerned these fingers are free to move to their lowermost positions. The parts are still further so

proportioned that if either roller is forced out of the notch in the point detector rod when the switch is locked in the extreme position in which the notch aligns with such roller, as by a train trailing the switch, the resulting movement of the associated point detector lever 91 will act through the associated operating rod 89, operating lever 86, pin 85, and open end slot 84 to rotate the contact operating member 82 in a clockwise direction, as viewed in Fig. 2, to such a position that the cams 81a and 81b will then engage the rollers 71a and 71b and will thus move the contact fingers to their upper positions in which they engage the contact member 63, but that, when the switch is moved from either extreme position to the other by the operating apparatus, the resulting movement of the camshaft 53 which takes place during the unlocking stroke of the slide bar N will act through the eccentric portions 67a and 67b of the bushings 66a and 66b and associated linkages to rotate the point detector levers to positions in which both rollers are clear of the point detector rod, and these rollers will be subsequently retained out of engagement with the point detector rod until the switch becomes locked in its reverse position.

It will be seen, therefore, from the foregoing that when the switch occupies its normal position in which it is shown in Fig. 3, and is locked in this position by the slide bar N, the notch 70a in the cam segment 69a will align with the roller 71a and the cam 81a will be out of alignment with the roller 71a as shown in Fig. 12, and under these conditions the fingers 60a will assume their lowermost positions in which the contacts 60a—62a are closed and the contacts 60a—63 are open. Likewise, when the switch occupies its reverse position, and is locked in this position by the slide bar N, the notch 70b in the cam segment 69b will align with the roller 71b and the cam 81b will be out of alignment with this roller, and the fingers 60b will therefore assume their lowermost positions in which the contacts 60b—62b are closed and the contacts 60b—63 are open. When, however, the switch is being moved from one extreme position to the other, the notch 70a in the cam segment 69a will be out of alignment with the roller 71a and the notch 70b in the cam segment 69b will also be out of alignment with the roller 71b, so that under these conditions both sets of contact fingers 60a and 60b will be moved to their raised positions in which the contacts 60a—62a and 60b—62b are open and the contacts 60a—63 and 60b—63 are closed.

It should be particularly noted that while the switch is being moved from either extreme position to the other, the tension springs 95a and 95b constantly exert a force on the contact operating member 82 which is considerably greater than that due to any friction which may exist between the operating lever 86 and the associated eccentric portions of the bushing 66 tending to rotate the contact operating member 82 in a clockwise direction, as viewed in Fig. 2, and that as a result the contact operating member remains stationary in the position in which the stop shoulder 82e engages the stop arm 101 during the reversal of the switch. Consequently, while the switch is being reversed the rotation of the eccentric bushings 66a and 66b resulting from the unlocking and locking strokes of the switch operating crank causes the operating levers 86a and 86b to traverse an orbit which slides the pins 85a and 85b longitudinally in the slots 84a and 84b, and which acts during the unlocking stroke of the

switch operating crank to move both rollers away from the point detector rod to positions in which both rollers are completely clear of the rod, and during the subsequent locking stroke to move both rollers toward the detector rod to such positions that at the end of the locking stroke the roller which was initially out of the notch in the detector rod will have entered this notch.

The contacts 60a—62a, 60b—62b, 60a—63 and 60b—63 of the circuit controller are usually referred to as the indication contacts, and their function is to so control signals governing traffic over the switch connected to the switch operating apparatus that these signals will indicate stop unless the switch points occupy their proper extreme positions relative to the stock rails and are locked in these positions. When, by error, the switch is trailed through, the switch points are displaced at the top an amount which would easily operate the circuit controller if the connection of the point detector rod with the switch points could be made at the top of the points. However, for clearance reasons, it is necessary to connect the detector rod to the switch points some distance below the top of the points where, due to the rolling of the points during the trailing, the amount of the movement may not be more than one-half of that occurring at the top; and furthermore, after a train has trailed through the switch, the points will usually spring back toward their original positions a certain amount. As a result, the final displacement of the point detector rod or rods may be very little, if any, more than the displacement which would correspond to a maximum permissible opening of the closed switch point, (which is the setting at which the circuit controller would be adjusted to operate the indication contacts), while the opening of the closed point at the top might be sufficient to be extremely dangerous for subsequent high speed train movements. In order to insure that this dangerous condition will be detected, I provide the circuit controller with latch mechanism for holding the indication contacts in their operated positions after they are once operated by displacement of the switch points until they are released by a maintainer. Thus, even though the switch points spring back toward their proper positions after the train has trailed through the switch, the signals governing traffic over the switch will continue to display a restrictive indication until the maintainer releases the latch and permits the contacts of the circuit controller to return to their normal positions. It is assumed that before the maintainer does this, he will inspect the switch points, and, if damaged, repair them, thus guarding against a dangerous condition due to damaged switch points.

This latch mechanism, as here shown, comprises a latching finger 105 which cooperates with a latch surface 82d formed on the yoke portion of the contact operating member 82 above the stop shoulder 82c. The latch finger 105 is pivotally supported intermediate its ends on a pin 106 mounted in upstanding lugs 107 provided on the frame 50, and is constantly biased to a latching position by means of a tension spring 108 stretched between the upper end of the latching finger and an upstanding lug 109 provided on the frame 50. When the contact operating member occupies its normal position in which it is shown in Fig. 2, the latching finger is held in engagement with the side of the contact operating member by means of the spring 108. When, however, the contact operating member is moved to its

contact operating position as by a train trailing the switch, the latch spring then rotates the latching finger into engagement with a stop lug 82e formed on the upper side of the yoke of the contact operating member 82. When in this latter position, the lower end of the latching finger overlies the latch surface 82d and prevents the contact operating member from returning to its normal position in which it is shown in Fig. 2. Thus, it will be seen that once the indication contacts are operated by operation of the point detector rod D, it will not be possible for the contact fingers 60a or 60b, as the case may be, to return to their lowermost positions until the latching finger is manually restored to its normal position, even though the switch points spring back to their normal positions in which the notch in the point detector rod aligns with the roller which was previously forced out of the notch to operate the contacts.

The switch operating apparatus further comprises auxiliary contact mechanisms for interrupting the motor circuit whenever the selector lever is moved away from the motor operating position to insure that the motor cannot be operated in a manner to cause injury to a person who is attempting to operate the switch machine by means of the hand lever, as well as for conditioning circuits for indicating at a remote point that the switch movement is in condition for manual operation. As here shown, this auxiliary contact mechanism comprises two flexible contact fingers 115 and 116 (see Figs. 1, 2, 10 and 12) which cooperate with fixed contact members 115a and 116a to form contacts 115-115a and 116-116a, respectively. The flexible contact fingers are supported in the proper positions to cooperate with the fixed contact fingers by means of supporting strips 117 and 118 secured to terminal posts 119 and 120 mounted on an insulating strip 121. The insulating strip 121 is secured to one side of the circuit controller frame 50 and serves as a support for other terminal posts connected to the previously described contact fingers 60a and 60b. The fixed contact members 115a and 116a are secured by means of screws 122 and 123 to supporting members 124 and 125 secured by means of terminal posts 126 and 127 to the insulating strip 121. The fingers are biased by their own resiliency to the positions in which they engage the associated fixed contact members, but are arranged to be at times moved out of engagement with the fixed contact members by means of insulating buttons 128 and 129 provided on upstanding arms 130 and 131 (see Fig. 14) forming part of a compound contact operating lever 132. The lever 132 is pivoted on a rod 133 mounted at its ends in bosses 134 formed on the sides of the housing 1, and is formed with a depending leg 135 which is pivotally connected with one end of an operating link 136. The link 136 rests by gravity on a shelf 137 formed in the bottom of the housing 1, and is provided with a tapered hole 138 which receives with slight clearance the tapered lower end of an operating arm 139. The arm 139 is secured at its upper end to one end of a rock-shaft 140 which extends transversely of the switch machine, and which is journaled intermediate its ends in spaced lugs 141 formed on a supporting bracket 142. The bracket 142, in turn, is secured to what is generally termed a gear box, which gear box is removable from the housing 1 as a unit, and which supports the shaft 6, the gear wheels 15 and 17 and associated clutch mechanism for selectively connecting these gear wheels with the

shaft 6. The rockshaft at the end opposite to the arm 139 has pinned thereto a second arm 143 which overlies and cooperates with the arm 35a of the shifter fork 35. A torsion spring 144 surrounds the rockshaft 140 between the lugs 141 and constantly biases the rockshaft in a clockwise direction as viewed in Fig. 2 to the position in which a stop screw 145 adjustably mounted in a laterally projecting lug 146 formed on the side of the arm 143 engages the side of the framework of the gear box. The stop screw is so adjusted that the arm 139 will normally be maintained by the torsion spring in the vertical position shown.

With the auxiliary contact mechanism arranged in this manner, when the selector lever occupies its motor operating position in which it is shown in Fig. 1, the torsion spring holds the arm 139 in its vertical position, and the parts are so proportioned that under these conditions, the arms 130 and 131 carrying the insulating buttons 128 and 129 will be held in their vertical positions and the buttons 128 and 129 will be out of engagement with the contact fingers 115 and 116. It follows, therefore, that when the selector lever occupies its motor operating position, the contacts 115-115a and 116-116a will be closed. When, however, the selector lever is operated from the motor operating to the hand throw position, the resultant upward movement of the shifter fork 35 will cooperate with the arm 143 to rotate the shaft 140 in a counterclockwise direction, as viewed in Fig. 2, in opposition to the bias of the spring 144, and this rotation, in turn, will act through the arm 139, link 136 and depending arm 135 to rotate the lever 132 and hence the arms 130 in the same direction. This latter rotation will move the insulating buttons 128 and 129 into engagement with the flexible fingers 115 and 116 and will thus move these fingers out of engagement with the fixed contact members 115a and 116a to open the contacts 115-115a and 116-116a. When the selector lever is subsequently restored to the position shown, the spring 144 will return the parts to the positions shown and will permit the contacts 115-115a and 116-116a to again become closed due to the inherent resiliency of the fingers.

It should be pointed out that while as shown the contacts 115-115a and 116-116a are normally closed, the fixed contact members 115a and 116a are so constructed that by removing the bolts 122 and 123 and turning these members over so that the contact buttons carried thereby face upwardly, instead of downwardly, these contacts can be converted from normally closed to normally open contacts which become closed when the selector lever is moved to the hand throw position.

It should also be pointed out that due to the fact that the only connection between the lever 139 and the link 136 is that provided by the tapered end of the lever and the tapered hole, the gear box can be removed at any time without the necessity for taking any precautions to disconnect the circuit controller since when the gear box is removed the lever 139 will lift out of the hole 138.

Although I have herein shown and described only one form of railway switch operating apparatus embodying my invention, it is understood that various changes and modifications may be made therein within the scope of the appended claims without departing from the spirit and scope of my invention.

Having thus described my invention, what I claim is:

1. In railway switch operating apparatus of the type in which a slide bar is moved to an intermediate position prior to the reversal of the switch points and to one or the other of two extreme positions upon the completion of the movement of the switch points depending upon the extreme position to which the switch points have been moved, the combination of a camshaft rotatable between two extreme positions in response to rotation of said slide bar between its two extreme positions, a contact operating member journaled on said camshaft, two pivoted point detector levers each provided with a roller, a point detector rod secured to the switch points to move therewith and provided with a notch which aligns with the roller carried by the one point detector lever when and only when the switch occupies its one extreme position and with the other roller when and only when the switch occupies its other extreme position, means biasing said point detector levers in directions tending to cause said rollers to enter said notch, two operating levers journaled on eccentric bushings mounted on said camshaft and operatively connected with said contact operating member and with said two point detector levers, respectively, said bushings being so disposed on said shaft that the roller on said one point detector lever is free to enter the notch in said point detector rod when and only when said slide bar occupies its one extreme position and that the roller on said other point detector lever is free to enter said notch when and only when said slide bar occupies its other extreme position, and a contact controlled by said contact operating member.

2. In railway switch operating apparatus of the type in which a slide bar is moved to an intermediate position prior to the reversal of the switch points and to one or the other of two extreme positions upon the completion of the movement of the switch points depending upon the extreme position to which the switch points have been moved, the combination of a camshaft rotatable between two extreme positions in response to rotation of said slide bar between its two extreme positions, a contact operating member journaled on said camshaft, two operating levers journaled on eccentric bushings mounted on said camshaft and operatively connected with said contact operating member, means connecting said levers with the switch points, said means being so constructed and said bushings being so disposed that one lever will occupy one extreme position when the slide bar and switch points occupy one extreme position and will be moved away from said one position at all other times and that the other lever will occupy one extreme position when the slide bar and switch points occupy another extreme position and will be moved away from such other position at all other times, and a contact controlled by said contact operating member.

3. In railway switch operating apparatus of the type in which a slide bar is moved to an intermediate position prior to the reversal of the switch points and to one or the other of two extreme positions upon the completion of the movement of the switch points depending upon the extreme position to which the switch points have been moved, the combination of a camshaft rotatable between two extreme positions in response to rotation of said slide bar between its two extreme positions, a contact operating mem-

ber journaled on said camshaft, two operating levers journaled on eccentric bushings mounted on said camshaft and operatively connected with said contact operating member and with the switch points, said eccentric bushings being angularly displaced on the shaft in such manner and the connections with the switch points and contact operating member being such that said operating member will be held in one extreme position except when said slide bar occupies one or the other of its extreme positions and the switch points are displaced from the corresponding extreme position, and a contact controlled by said contact operating member.

4. In railway switch operating apparatus of the type in which a slide bar is moved to an intermediate position prior to the reversal of the switch points and to one or the other of two extreme positions upon the completion of the movement of the switch points depending upon the extreme position to which the switch points have been moved, the combination of a camshaft rotatable between two extreme positions in response to rotation of said slide bar between its two extreme positions, a contact operating member journaled on said camshaft, two operating levers journaled on eccentric bushings mounted on said camshaft and operatively connected with said contact operating member and with the switch points, said eccentric bushings being angularly displaced on the shaft in such manner and the connections with the switch points and contact operating member being such that said operating member will be held in one extreme position except when said slide bar occupies one or the other of its extreme positions and the switch points are displaced from the corresponding extreme position, and a contact controlled by said contact operating member, and means for preventing said contact operating member from returning to its one extreme position after it is moved away from such extreme position until it is manually released.

5. In railway switch operating apparatus of the type in which a slide bar is moved to an intermediate position prior to the reversal of the switch points and to one or the other of two extreme positions upon the completion of the movement of the switch points depending upon the extreme position to which the switch points have been moved, the combination of a camshaft connected to said slide bar for rotation between two extreme positions in response to movement of said slide bar between its two extreme positions, a first and a second cam mounted on said camshaft to rotate therewith, a point detector rod secured to the switch points to move therewith and provided with a notch, two pivoted point detector levers each provided with a roller and each biased in a direction which tends to cause the roller carried thereby to enter said notch, said notch being so disposed that it will align with the roller on the one lever when and only when the switch occupies its one extreme position and with the roller on the other lever when and only when the switch occupies its other extreme position, a contact operating member journaled on said camshaft and provided with third and fourth cams, a first contact controlled by said first and third cams, a second contact controlled by said second and fourth cams, two operating levers journaled on eccentric bushings mounted on said camshaft and operatively connected with said contact operating member and with said two point detector levers, respectively,

said eccentric bushings being so arranged that the roller on the one point detector lever is free to enter the notch in said point detector rod when and only when said slide bar occupies its one extreme position and that the roller on the other point detector lever is free to enter the notch in said point detector rod when and only when said slide bar occupies its other extreme position.

6. In a point detector for switch operating apparatus of the type including a slide bar for locking the switch points in their two extreme positions, a camshaft operatively connected with said slide bar, a pair of bushings mounted on said camshaft and each provided with a portion concentric with respect to said shaft and a portion eccentric with respect to said shaft, a U-shaped contact operating member having its arms journaled intermediate their ends on the concentric portions of said bushings and provided at their free ends with open end slots, operating levers journaled on the eccentric portions of said bushings and each provided with a first arm carrying a pin slidably mounted in said slots and with a second arm, a pair of pivoted point detector levers each provided with an arm operatively connected by means of a link with the second arm of a corresponding one of said operating levers, each said point detector lever also being provided with a roller, a point detector rod connected with the switch points and provided with a notch which aligns with the roller carried by one point detector lever when and only when the switch occupies one extreme position and with the roller carried by the other point detector lever when and only when the switch occupies its other extreme position, said bushings being disposed on said shaft in such relative positions that the rollers carried by said point detector levers are free to enter the notch in said point detector rod when and only when such notch aligns with the roller and the slide bar occupies a corresponding locking position, spring means biasing said point detector levers to the positions in which said rollers enter said notch, means for limiting the rotation of said contact operating member due to said spring means, and a contact operated in accordance with the position of said contact operating member.

7. In a point detector for switch operating apparatus of the type including a slide bar for locking the switch points in their two extreme positions, a camshaft operatively connected with said slide bar, a pair of bushings mounted on said camshaft and each provided with a portion concentric with respect to said shaft and a portion eccentric with respect to said shaft, a U-shaped contact operating member having its arms journaled intermediate their ends on the concentric portions of said bushings and provided at their free ends with open end slots, operating levers journaled on the eccentric portions of said bushings and each provided with a first arm carrying a pin slidably mounted in said slots and with a second arm, a pair of pivoted point detector levers each provided with an arm operatively connected by means of a link with the second arm of a corresponding one of said operating levers, each said point detector lever also being provided with a roller, a point detector rod connected with the switch points and provided with a notch which aligns with the roller carried by one point detector lever when and only when the switch

occupies one extreme position and with the roller carried by the other point detector lever when and only when the switch occupies its other extreme position, said bushings being disposed on said shaft in such relative positions that the rollers carried by said point detector levers are free to enter the notch in said point detector rod when and only when such notch aligns with the roller and the slide bar occupies a corresponding locking position, spring means biasing said point detector levers to the positions in which said rollers enter said notch, means for limiting the rotation of said contact operating member due to said biasing means, first and second cams formed respectively on the two arms of said contact operating member, third and fourth cams mounted on said camshaft for rotation therewith adjacent the two arms of said contact operating member, contacts controlled by said first and third cams, and other contacts controlled by said second and fourth cams.

8. In a point detector for switch operating apparatus of the type including a slide bar for locking the switch points in their two extreme positions, a camshaft operatively connected with said slide bar, a pair of bushings mounted on said camshaft and each provided with a portion concentric with respect to said shaft and a portion eccentric with respect to said shaft, a U-shaped contact operating member having its arms journaled intermediate their ends on the concentric portions of said bushings and provided at their free ends with open end slots, said contact operating member being rotatable between a normal and a contact operating position, operating levers journaled on the eccentric portions of said bushings and each provided with a first arm carrying a pin slidably mounted in said slots and with a second arm, a pair of pivoted point detector levers each provided with an arm operatively connected by means of a link with the second arm of a corresponding one of said operating levers, each said point detector lever also being provided with a roller, a point detector rod connected with the switch point and provided with a notch which aligns with the roller carried by the one point detector lever when and only when the switch occupies one extreme position and with the roller carried by the other point detector lever when and only when the switch occupies its other extreme position, said bushings being disposed on said shaft in such relative positions that the rollers carried by said point detector levers are free to enter the notch in said point detector rod when and only when such notch aligns with the roller and the slide bar occupies a corresponding locking position, spring means biasing said point detector levers to the positions in which said rollers enter said notch, the parts being so proportioned that said contact operating member will be rotated to its normal position at all times except when the switch is locked in either extreme position and neither roller is within said notch, a latching finger biased to a latching position and effective when said contact operating member is moved to its contact operating position to latch said contact operating member in such position until said finger is manually operated to release said contact operating member, and a contact controlled by said contact operating member.

HERBERT L. BONE.
